CLAIM

The ornamental design for a dog cage assembly, as shown and described.

DESCRIPTION

FIG. 1 is a front perspective view of the left part of a dog cage assembly, showing my new design;

FIG. 2 is a front view of the left part thereof;

FIG. 3 is a rear view of the left part thereof;

FIG. 4 is a left side view of the left part thereof;

FIG. 5 is a right side view of the left part thereof;

FIG. 6 is a top view of the left part thereof;

FIG. 7 is a bottom view of the left part thereof;

FIG. 8 is a front perspective view of the right part thereof;

FIG. 9 is a front view of the right part thereof;

FIG. 10 is a rear view of the right part thereof;

FIG. 11 is a left side view of the right part thereof;

FIG. 12 is a right side view of the right part thereof;

FIG. 13 is a top view of the right part thereof;

FIG. 14 is a bottom view of the right part thereof;

FIG. 15 is a perspective view of combined state 1 thereof;

FIG. 16 is a perspective view of combined state 2 thereof; and,

FIG. 17 is a perspective view of combined state 3.

The broken lines in the drawings illustrate the portions of the dog cage assembly, which form no part of the claimed design.

1 Claim, 17 Drawing Sheets
